FIG. 1 is a perspective view of the wearable medical monitor of the present invention;

FIG. 2 is a top view of the wearable medical monitor of FIG. 1;

FIG. 3 is a bottom view of the wearable medical monitor of FIG. 1;

FIG. 4 is a front view of the wearable medical monitor of FIG. 1;

FIG. 5 is a rear view of the wearable medical monitor of FIG. 1;

FIG. 6 is a right side view of the wearable medical monitor of FIG. 1; and,

FIG. 7 is a left side view of the wearable medical monitor of FIG. 1.

The broken lines shown in the drawings illustrate portions of the wearable medical monitor that form no part of the claimed design.
